UNITED STATES PATENT OFFICE.

SIDNEY DAVIS, OF LANKERSHIM, CALIFORNIA.

MAIL-BOX INDICATOR.

1,370,196.

Specification of Letters Patent.

Patented Mar. 1, 1921.

Application filed May 27, 1920. Serial No. 384,695.

To all whom it may concern:

Be it known that I, SIDNEY DAVIS, a citizen of the United States, residing at Lankershim, in the county of Los Angeles and State of California, have invented new and useful Improvements in Mail-Box Indicators, of which the following is a specification.

This invention is an indicator for mail boxes and the like and has for its object the provision of an indicator of simplified construction and one which is arranged to form a part of the usual retaining latch for the door of the box.

15 It is a further object of the invention to provide an indicator arranged to display a plurality of indicating means which may be observed from different directions beyond the box, this plurality of indicating means being so connected for dependent actuation that turning of one of said indicating means to either operative or inoperative position will cause similar movement of the other indicating means.

25 The invention will be readily understood from the following description of the accompanying drawings, in which—

Figure 1 is a side elevation of the improved indicator partly in section, and shown in operative position applied to a mail box.

Fig. 2 is a front end view of the same.

Fig. 3 is a rear end view of the same.

Fig. 4 is a top plan view of the invention with the parts in inoperative position.

Fig. 5 is a view, similar to Fig. 1, of a modified form of the invention in which only one indicator is employed.

Fig. 6 is a section on the line 6—6 of Fig. 5.

The improved indicator is shown as applied to a usual mail box including a top 1 and a hinged front door 2. A hook handle 3 is shown as provided upon the door 1 adjacent the upper edge thereof, this hook handle being provided with a retaining lug 4 adapted to be engaged in a suitable recess provided in a co-operating latching member secured upon the top of the box. This 45 latching member, preferably, forms a base upon which the improved indicator is mounted.

As an instance of this arrangement the latching member is shown as a strip 5 pro-

jecting beyond the front edge of the top of the mail box and provided with a recess 6 for engaging lug 4 and, preferably, also provided with an upturned front end 7 forming a rest for the thumb when the fingers grasp the handle 3. The strip 5 is, 60 preferably, riveted or otherwise secured to the top of the mail box adjacent its rear end as shown at 8 so that the front end of the strip will have sufficient play relative to the mail box to permit of disengagement of the 65 lug 4 from recess 6.

The mounting for the improved indicator provided by the strip 5 comprises an upturned lug 9 upon said strip in rear of recess 6 and an upturned rear end 10 upon the 70 strip. The lug 9 is provided with a suitable bearing opening 11, and the upturned end 10 is reversely bent at its upper end to provide a bearing opening 12.

The indicator, preferably, comprises two 75 signal plates arranged at right angles to one another so that said plates may be observed from different directions beyond the mail box. One of these signal plates shown at 13 is provided with a reversed bend 14 along 80 the lower edge thereof received around a rod 15 which extends through this bend and is journaled in the opening in lug 9 and in a suitable opening 16 provided in the upturned end 10. The front end of rod 15 is, 85 preferably, upturned as shown at 17 and is received within a bearing formed by a reverse bend 18 at the edge of the signal plate. The second signal plate is shown at 19 journaled upon a pin 20 extending through the 90 bearing 12, the signal plate for this purpose being provided with a reversely bent lower edge forming bearings 21 adjacent the respective side edges of the plate and through which the ends of pin 20 extend beyond the 95 bearing 12.

The reverse bend at the lower edge of plate 19 is, preferably, extended outwardly at the respective bearings 21 to form lips 23. The reverse bend at the lower edge of plate 100 19 between bearings 21, preferably, extends upwardly an appreciable distance and terminates in a hook 24. The end of rod 15 beyond the bearing opening 16 is upturned as shown at 25 so as to have its end received 105 in the hook 24 when the parts are in operative position as shown in Fig. 1. The upper edge of plate 19 is, preferably, slightly

outwardly bent as shown at 26 and is provided with a medial notch 27 arranged to engage the edge of plate 13 when the parts are in operative position for retaining the two plates in their relative positions.

In operation when it is desired to lower the signal plates from their indicating position, as shown in Fig. 1, the plate 13 and the rod 15 are turned in bearings 11 and 16 so as to swing plate 13 from upright position to a substantially horizontal position. The upturned end 25 of rod 15 will at the same time be turned from upright position engaging hook 24 into substantially a horizontal position. This turning movement of the upright end of rod 15 will cause the latter to abut against one or the other of lips 23 and thereby swing plate 19 rearwardly and downwardly upon the pivot formed by rod 20.

When it is again desired to raise the signal plates to operative position the plate 13 will be swung upwardly and the corresponding swinging movement of the upturned end 25 of rod 15 will cause said rod to abut against the reversely bent hook portion 24 of plate 19 and thereby also swing this plate into upright position. When the two plates have been moved to upright position the edge of plate 13 engaging in the notch 27 will hold the plates in their operative position.

In the modification of the invention illustrated in Figs. 5 and 6 only the plate 13 is employed, the means provided for retaining this plate in upright position and permitting of swinging movement thereof into inoperative position being shown as comprising a spring, preferably, a leaf spring 30 mounted upon the strip 5 beneath the bearing 14 and having its free end engaging a flattened portion 31 provided upon the under side of bearing 14 for yieldably retaining the plate 13 in upright position.

Various changes may be made without de-

parting from the spirit of the invention as 45 claimed.

What is claimed is:

1. An indicator comprising a signal plate pivoted for swinging movement downwardly from upright signaling position and 50 fixed against axial movement, and spring means having its free end abutting against the pivotal bearing of said signal plate for yieldably retaining said plate in upright position.

2. An indicator comprising independently pivoted signal plates angularly disposed relative to one another and arranged for dependent swinging movement downward from upright signaling position.

3. An indicator comprising independently pivoted signal plates angularly disposed relative to one another and arranged for dependent swinging movement downward from upright signaling position, and a resilient member for yieldably retaining both of said plates in upright position.

4. An indicator comprising signal plates angularly disposed relative to one another and arranged for dependent swinging movement downward from upright signaling position, said plates arranged to engage one another for yieldably retaining the same in upright position.

5. An indicator comprising signal plates 75 angularly disposed relative to one another and arranged for swinging movement downward from upright position, and means carried by one of said plates for engaging the other plate to cause dependent swinging 80 movement of said plates downwardly and upwardly, said plates being arranged to engage one another for yieldably retaining the same in upright position.

In testimony whereof I have signed my 85 name to this specification.

SIDNEY DAVIS.
